Francis J. Carroll,

INVENTOR

P. J. Hickey

WITNESS:

BY *Victor J. Evans & Co.*

ATTORNEY

UNITED STATES PATENT OFFICE

FRANCIS J. CARROLL, OF NEW BEDFORD, MASSACHUSETTS

PRINTING ROLLER

Application filed December 14, 1931. Serial No. 580,970.

This invention relates to printing rollers for use in rotary printing machines employed in the textile printing art and has for the primary object, the provision of a device 5 of the above stated character which will be efficient in operation, light in weight, and which may be manufactured at a low cost and consist of an outer seamless shell of non-ferrous metal filled with an inert material under pressure so as to reinforce the shell 10 and provide the same with sufficient strength to withstand forces acting thereon and to provide the device with a bore of the desired mandrel size, thereby rendering the device 15 interchangeable on mandrels of a given size.

With this and other objects in view, this invention consists in certain novel features of construction, combination and arrangement of parts to be hereinafter more fully described 20 and claimed.

For a complete understanding of my invention, reference is to be had to the following description and accompanying drawing, in which

25 Figure 1 is a sectional view illustrating a printing roller constructed in accordance with my invention.

Figure 2 is a sectional view taken on the line 2—2 of Figure 1.

30 Figure 3 is a transverse sectional view illustrating a modified form of my invention.

Referring in detail to the drawing, the numeral 1 indicates a mandrel of a rotary printing machine on which a roller 2 is mounted and the latter includes an outer seamless shell 3 of non-ferrous material preferably constructed from copper and on which is formed the desired design to be printed on textile or fabric. An inner sleeve 4 is arranged concentrically within the outer shell 3 and provides a bore to receive the mandrel 1 and may be provided with a key to fit the keyway of the mandrel. Spacing disks 5 are arranged between the inner sleeve and the shell 3 and are secured to said sleeve and shell in any suitable way such as welding. The end disks form heads for the roller.

During the construction of the roller 1, inert material 6 is placed within the shell 3 under pressure to provide a reinforcement for

the shell so that the latter is capable of withstanding forces acting thereon. The material 6 also forms the bore to receive the inner sleeve 4 or if desired the inner sleeve 4 may be omitted and the bore formed by the material 6 being of such a size as to receive a mandrel either of the cylindrical or cone type. When the sleeve 4 is omitted, radially disposed reinforcing elements 7 are embedded within the inert material 6 and preferably 55 are of non-ferrous material.

A roller constructed in accordance with the foregoing may be manufactured at a much lower cost than the conventional type of roller now in use and which is constructed from 60 solid metal, also this construction produces a lightness in weight which is advantageous in handling and shipping due to the fact that the cost of shipping will be materially reduced.

A roller constructed in accordance with the foregoing will have no internal strains set up therein, thus eliminating distortion and it can be seen that no turning is necessary to true 65 the roller before engraving the outer periphery of the shell, and the lack of distortion will permit the roller to run equally true on a cone or on a mandrel, thus having a distinct advantage both to the engraver and the printer.

A roller constructed in accordance with the foregoing will have a much lower cost of maintenance than the conventional type of rollers and it is to be noted that a pattern engraved on the outer circumference of the 70 shell may be turned off and another pattern substituted therefor when desired, it being understood that the outside of the shell may be built up to its original circumference, thus rendering a substantial saving to the operator in cost.

While I have shown and described the preferred embodiment of my invention, it will be understood that minor changes in construction, combination and arrangement of 75 parts may be made without departing from the spirit and scope of my invention, as claimed.

Having thus described my invention, what I claim is:

A printing roller, comprising an outer seamless shell of non-ferrous material adapted to have a design applied to its outer face, an inner sleeve arranged concentrically with-
5 in said shell to rotatably receive a shafting, a
filler of an inert material placed between the
sleeve and shell under pressure, and discs
secured to said shell and sleeve and embedded
in the filler to reinforce the latter and to sup-
10 port the outer shell relative to the inner sleeve.

In testimony whereof I affix my signature.
FRANCIS J. CARROLL.
